UNITED STATES PATENT OFFICE.

BENJAMIN S. DEAN, OF SAN FRANCISCO, CALIFORNIA.

SELF-PLAYING MUSICAL INSTRUMENT.

No. 862,061.

Specification of Letters Patent.

Patented July 30, 1907.

Application filed March 23, 1906. Serial No. 307,570.

To all whom it may concern:

Be it known that I, BENJAMIN S. DEAN, a citizen of the United States of America, and resident of San Francisco, county of San Francisco, State of California, have 5 invented certain new and useful Improvements in Self-Playing Musical Instruments and Musical-Instrument Players, of which the following is a specification, reference being had to the accompanying drawings, forming a part thereof.

10 My invention relates to improvements in self-playing musical instruments and musical instrument players of the type employing perforated music record sheets for controlling the instrument.

In the present instrument I employ a music record 15 comprising two sheet members adapted to be simultaneously caused to travel over two separate trackers, and it is the main object of the present invention to provide for an adjustment whereby compensation may be made for inequalities in travel of the two sheet 20 members.

To this end my invention consists in providing means for adjusting the two trackers with respect to each other so as to cause same to move backwards and forwards with relation to the direction of movement of the sheet 25 members which travel thereover, such means being automatically controlled by the said music record sheet members.

In order that my invention may be fully understood, I will now proceed to describe an embodiment thereof 30 with reference to the accompanying drawings illustrating same, and will then point out the novel features in claims.

In the drawings: Figure 1 is a view in partial end elevation and partial vertical transverse section, showing 35 two trackers and compensating means therefor, together with two record sheet members employed in connection therewith. Fig. 2 is a detail view of a rocking beam employed therein, together with certain co-related parts, viewed at right angles to the point of view of 40 Fig. 1. Fig. 3 is a detail face view of the trackers at one end thereof. Fig. 4 shows a fragmentary view, of a part of one of the music sheet members near one edge thereof.

The two trackers are illustrated at 1 and 2 in the drawings, the perforations therein for controlling the 45 tones to be produced being designated by the reference character 3. In addition to the perforations 3, there are other perforations, two of which (one in each tracker board), I, will term herein rectifying perforations 4. The trackers 1 and 2 are pivoted at points 5 to parts 50 stationary in the device, upon which points they are adapted to have a relative swinging movement. The two trackers 1 and 2 are provided with outwardly projecting arms 6, which are connected 1. links 7, such arms and links compelling complementary movements 55 between the two trackers always in opposite directions. The two record sheet members 8 and 9 are shown as

being paid off from the same roller 10, but the individual members are taken up on separate take-up rollers 11 and 12. The members 8 and 9 pass over and under a guide piece 13, then over their respective trackers 1 and 2 to the take-up rollers 11, 12; as is shown in the drawings.

The rectifying orifices of the trackers are connected by means of tubes 14 and 15 with primary pneumatic devices 16, 17. These primary pneumatic devices 65 comprise stationary cylindrical studs 18 to which are fitted with a sliding fit, domes 19, and springs 20 arranged between the domes and the studs to normally force the said domes upward. The studs have an opening 21 therethrough leading through a passage 22 and 70 port 23 to a vacuum chamber 24. Screws 25 are employed at various points to regulate the amount of air allowed to pass selected points at given times. The two pneumatic devices 16, 17 are arranged to actuate a rocker beam 26. This rocking beam is in the shape of an 75 inverted L or double bell crank lever, the lateral arms of which engage the pneumatic devices, and the vertical arm of which is adapted to contact with, and operate, valve rods 27, 28. Each of the rods 27, 28 carries inlet and discharge valves 29, 30, arranged to control 80 the admission and exhaust of air from secondary pneumatic devices 31, 32. The domes of these secondary pneumatic devices are connected with an arm 33, said arm being secured to, or constructed as a part of, the arms 6 of the lower tracker 2. Thus, by moving the 85 arm 33 backwards and forwards, relative movements in opposite directions will be imparted to the trackers 1 and 2 as will be well understood. The record sheet members are provided near one of their edges with openings 34 arranged to register with the rectifying orifices 4 of the trackers. The openings 34 are arranged to exactly correspond in both the music sheet members, so that, in the normal running of the record sheets, the said perforations 34 will register synchronously with the rectifying orifices 4 in both the said trackers 1 and 2. 95

Bearing in mind that the effect of a perforation 34 registering with an orifice 4 is to vent air into one or other of the primary pneumatic devices 17, 18, thereby to raise the air pressure within the pneumatic device so affected and permit the spring 20 therein to operate, 100 it will follow that the sheet members, when running normally, will cause synchronous impulses to be given at predetermined intervals to both the primary pneumatic devices 16, 17, with the result that the rocking beam 26 will be reciprocated in right lines. This reciprocation will have no effect whatever upon the rods 27, 28 or the valves carried thereby, and hence there will be no effect upon the secondary pneumatic devices, and the trackers will be maintained in a relatively stationary position. If, however, one record sheet member begins to creep slightly forward with respect to the other, the rectifying orifice 4 in the corresponding 105

tracker will be opened ahead of the other, with the effect that one of the primary pneumatic devices 16, 17 will be operated ahead of the other and the beam 26 thereby tipped. Say, for example, air is vented into the pneumatic device 16 in advance of the device 17. This will tip the beam 26 over to the right, causing the valve 29 of the secondary pneumatic device 32 to be opened and the valve 30 to be closed. The secondary pneumatic device 32 will then be opened to vacuum, and the arms 33 and 6 will be swung upon their pivots 5 and relative movements imparted to the trackers 1 and 2. The relative movements of the trackers will be such as to compensate for the advance movement of one record sheet member over the other, as is desired.

15. In order to prevent the compensating movement just described from being neutralized by operation of the other pneumatic device upon venting of air through the rectifying orifice 4 in the other tracker (namely, that which is later opened), I provide a special means by which, when the beam has been once tipped, it cannot be straightened out by a release movement until both the pneumatic devices are again under tension and the beam has been drawn down to its normal horizontal lowermost position. This means is comprised 20 in pins 35 carried by the vertical arm of the beam 26, which are arranged upon opposite sides of a central flat steel spring 36. This steel spring is connected at its upper end with the arm 33, and at its lower end to a fixed point in the device. The said spring has a cut-away portion 37, as will be seen more clearly by reference to Fig. 2, the pins 35 being arranged opposite the cut-away portion while the beam is in its lowermost position. When the beam 26 is tilted, the pins 35 will both pass upon one side or the other of the steel spring 36, and thus, upon upward movement thereof, will cause the beam to be raised in its tilted position and prevent the beam from being drawn to a horizontal position until it has been again drawn down to its lowermost position, because it is only at the lowermost position that the pins may pass freely through the slotted portion 37; at other times they will be impeded in their movement by engagement with the spring piece 36. At its lower end the beam 26 is provided with pins 38, also arranged upon opposite sides of the steel spring 36, 40 but these pins are solely guide pins to assist in guiding the beam 26 in its folding movements.

What I claim is:

1. In a device of the character described, the combination with a plurality of separate trackers over which music record sheets are adapted to travel, of means automatically controlled in the operation of the instrument for adjusting the trackers with respect to each other in the direction of travel of the said music record sheets.
2. In a device of the character described, the combination with a plurality of trackers arranged to receive a plurality of music sheet members to correspond with the said trackers, of means automatically controlled in the normal operation of the device for imparting relative movements of compensation to the trackers to compensate for unequal travel of the music sheet members.
3. In a device of the character described, the combination with two independent trackers, and music record means comprising two perforated sheets arranged to travel over the individual trackers, of means controlled by the music record means for relatively adjusting the said trackers with respect to each other in the direction of travel of the said perforated sheets.
4. In a device of the character described, the combination with a tracker arranged for co-action with a music

record sheet, of means controlled by the record sheet in its travel over the tracker to adjust the position of the tracker in the direction of travel of the music sheet.

5. In a device of the character described, the combination with two pivotally mounted trackers connected together whereby they are rocked simultaneously in opposite directions, of means controlling the said rocking movements thereof.

6. In a device of the character described, the combination with two pivotally mounted trackers connected together whereby they are rocked simultaneously in opposite directions, said trackers arranged for co-operation with music record means comprising two separate perforated sheets, of means controlled by the music record means in the movement thereof over the trackers for imparting rocking movements to the said trackers.

7. In a device of the character described, the combination with tracker means comprising two separate trackers over which music record sheets are adapted to travel, of primary pneumatic devices connected with openings in said tracker means, and, secondary pneumatic means controlled by said primary pneumatic devices for adjusting the trackers with respect to each other in the direction of travel of the said music record sheets.

8. In a device of the character described, the combination with two pivotally mounted trackers connected together whereby they will rock simultaneously in opposite directions, of pneumatic means controlled through said trackers for imparting such rocking movements thereto.

9. In a device of the character described, the combination with two trackers over which music record sheets are adapted to travel, of pneumatic means for adjusting the position of said trackers with relation to each other in the direction of travel of the said music record sheets, said pneumatic means controlled through openings in the said trackers.

10. In a device of the character described, the combination with two trackers, of pneumatic means for adjusting the position of said trackers with relation to each other, said pneumatic means controlled through openings in the trackers in accordance with which opening is uncovered first, and means for preventing the later uncovering of the corresponding opening in the other tracker from restoring the parts to their pre-adjusted positions.

11. In a device of the character described, the combination with two trackers, of pneumatic means connecting with said trackers through openings therein, means whereby the uncovering of the opening in one of the said trackers prior to the uncovering of the other will cause the said trackers to be adjusted with respect to each other in one direction, and means whereby adjustment will not be effected in the other direction until the opening in the other said tracker is uncovered prior to the opening in the first said tracker.

12. In a device of the character described, the combination with two trackers, of pneumatic means connecting with said tracker through openings therein, means whereby the uncovering of the opening in one of the said trackers prior to the uncovering of the other will cause the trackers to be adjusted with respect to each other in one direction, and means whereby adjustment will not be effected in the other direction until the opening in the other said tracker is uncovered prior to the opening in the first said tracker, and whereby the simultaneous uncovering of the two said openings shall affect no adjustment of the said trackers one way or the other.

13. In a device of the character described, the combination with two pivotally mounted trackers connected together whereby they will rock simultaneously in opposite directions, primary pneumatic means in connection with each said tracker, a rocking beam connected with, and operated by, said primary pneumatic means, secondary pneumatic means connected mechanically with said trackers, and valves controlling said secondary pneumatic means operated by movements of said rocking beam.

In witness whereof I have hereunto set my hand in the presence of two witnesses.

BENJAMIN S. DEAN.
